VACUUM THERMAL INSULATING PANEL

John F. P. Tate, New York, N. Y.

Application October 19, 1948, Serial No. 55,349
In Canada May 14, 1948

2 Claims. (Cl. 189—34)

1. This invention relates to new and useful improvements in vacuum thermal insulating panels. This application is a substitute for my abandoned application, Serial No. 499,758, filed August 24, 1943.

More particularly, the invention proposes to characterize the new panel by a pair of end bridge plates rigidly held in spaced position with one or more struts and associated with side plates or bridge plates mounted between the edge portions of said first named bridge plates. It is proposed to provide a cover sheet of flexible material mounted across the top and bottom edges of said bridge plates and said side or bridge plates, and sealed thereon forming a hermetically sealed hollow panel. It is proposed that the air from within said panel be exhausted to a partial vacuum. It is further proposed that the top and bottom walls of said cover sheets be concaved to a position and condition simulating the natural forming of said flexible cover sheet due to the difference between atmosphere pressures and the internal pressure of the panel.

The new panel may be made of sheet steel or other suitable sheet metals or materials and may be used in single, or multiple units to form thermal insulating walls for buildings, heating or steam generating equipment, oven or cold storage compartments, or for any other application of spatial enclosure insulation. It is proposed that said partial vacuum be permanently maintained within the panel and that it be for the purpose of retarding the transmission of heat by conduction or convection from one side of the panel to the other. It is also proposed that the surface of the outer cover be burnished to resist heat transmission through the panel by radiation.

It is pointed out that in service the hollow panel will be subjected to an internal and external pressure differential, the external pressure being that of the atmosphere or other surrounding medium, the internal pressure being that of the rarified air or gas remaining after the panel interior has been evacuated to a practical limit.

It is proposed that the structural resistance of the panel to distortion from the unequal pressures mentioned above will be cared for by the tensile resistance of the outer cover reacting against the internal struts and side or bridge plates. Under the greater external pressure the outer cover will assume an approximately parabolic profile.

It is proposed that the new panel unit for and during its manufacture be provided with an

exhaust opening and stop valve through which the interior may be evacuated by means of a vacuum pump. It is proposed that after the interior has been so evacuated, that the opening will be suitably and permanently sealed to prevent subsequent leakage.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a vacuum thermal insulating panel constructed according to this invention.

Fig. 2 is a sectional view taken on the line 2—2 of Fig. 1.

Fig. 3 is a sectional view taken on the line 3—3 of Fig. 1.

Fig. 4 is a fragmentary elevational view of a vacuum thermal insulating panel constructed according to a modified form of this invention.

Fig. 5 is a sectional view taken on the line 5—5 of Fig. 4.

Fig. 6 is a sectional view taken on the line 6—6 of Fig. 4.

Fig. 7 is a perspective view of the bridge plates, struts, and side plates used in the form of the invention disclosed in Figs. 4 to 6.

Fig. 8 is a side elevational view of a vacuum thermal insulating panel constructed in accordance with another form of this invention.

Fig. 9 is a fragmentary elevational view looking in the direction of the line 9—9 of Fig. 8.

Fig. 10 is a perspective view of the bridge plates, struts, and side plates used in the form of the invention shown in Figs. 8 and 9.

The vacuum thermal insulating panel, in accordance with the form of the invention disclosed in Figs. 1 to 3, includes pairs of end bridge plates 10 and side bridge plates 10^a formed with bevelled ends and welded together to form a rectangular frame and additionally rigidly held in relatively spaced positions with rigid struts 11. The bridge plates 10 and 10^a are shown as of V-shape in transverse cross section but turned around 90° so that their apexes are towards each other. The struts 11 are fixedly mounted between the apexes of the said V-shapes.

Side plates 12 are mounted against the side bridge plates 10^a. These side plates 12 are illustrated as of rectangular shape. A cover sheet 14 of flexible material, preferably sheet metal,

is mounted across the top and bottom edges of the bridge plates 10 and 10^a and the side plates 12 and is sealed thereon preferably by welding these parts together. This sealing forms a hermetically sealed hollow panel, and it is proposed that the air of this panel be partially exhausted to form a partial vacuum.

It is an important feature of this invention that the top and bottom walls 15 and 16 of said cover sheet 14 be concaved to a position and condition simulating the natural forming of said flexible sheet 14 due to the difference between atmospheric pressure and the internal pressure of said panel. The cover sheet 14 is shown to have end portions 14^a and 14^b located at one or both ends of the panel and secured together with a continuous butt-weld 17.

In Fig. 2 added weld material 18 is shown securing the edge portions of the side plates 12 to the edge portions of the cover sheet 14. It should be noted that the edge portions of the cover sheet 14 project a small amount past the outer face of the side plates 12.

It is proposed that the interior of the panel be suitably exhausted and sealed. One end of the panel is initially formed with an aperture 19. A tube 20 is mounted upon the inner faces of the cover sheet 14 around said aperture 19. This tube 20 is provided with a one-way valve 21. The side arms of the bridge plates 10 and 10^a are formed with vent openings 22 through which the air within the panel may circulate. After the air has been partially withdrawn it is proposed that a plug 23 be engaged in the opening 19 and sealed therein, preferably with welding.

In Figs. 4 to 7 a modified form of the invention is shown which distinguishes from the prior form in several respects. In this form of the invention the end bridge plates 10' extend the complete height of the panel. The side plates 12' are set in slightly from the ends of the bridge plates 10' and are fixedly connected with the bridge plates by welding material 18. The side plates 12' have concaved edges to conform with the substantially parabolic profile of the cover sheet 14'. In view of the fact that the side plates 12' do not extend across the openings between the arms of the bridge plates 10', the tube 20 and the valve 21 is mounted upon one of the arms of one of the bridge plates 10'. In other respects this form of the invention is similar to that previously shown and like reference numerals identify like parts in each of the several views.

In Figs. 8 to 10 another form of the invention has been disclosed which distinguishes from the prior forms essentially in design. In this form of the invention the bridge plates 10'' are shown of greater length than the side plates 12''. The bridge plates 10'' are shown connected together with a plurality of struts 11''. A cover sheet 14'' is mounted on the bridge and side plates.

In other respects this form of the invention is identical to the previous forms and like parts are indicated by like reference numerals.

While I have illustrated and described the preferred embodiments of my invention, it is to be understood that I do not limit myself to the

precise construction herein disclosed and the right is reserved to all changes and modifications coming within the scope of the invention as defined in the appended claims.

Having thus described my invention, what I claim as new and desire to secure by United States Letters Patent is:

1. A heat insulating panel comprising a pair of spaced apart V-shaped bridge plates positioned with their apexes facing one another, struts extended between the apexes of said bridge plates, plates extended between the ends of said bridge plates and secured thereto, and elongated cover plates of a width corresponding to the spacing of said second plates and secured to the longitudinal edges of said bridge plates and said second plates, said cover plates being of a length greater than the spacing of said bridge plates to have extensions at either end equal in width to one-half the distance between the longitudinal edges of the legs of said bridge plates, said extensions being bent at right angles to said cover plates to extend about the longitudinal edges of said bridge plates with adjacent extensions abutting one another and secured together in edge contact.
2. A heat insulating panel comprising a pair of spaced apart V-shaped bridge plates positioned with their apexes facing one another, side plates extended between the end of said bridge plates and secured to the ends of said bridge plates with the corners of said side plates arranged flush with the corners of said bridge plates, and elongated cover plates of a width corresponding to the spacing of said side plates secured to the longitudinal edges of said bridge plates and said side plates, said cover plates being of a length greater than the spacing of said bridge plates to have extensions at either end equal in width to one-half the distance between the longitudinal edges of the legs of said bridge plates, said extensions being bent at right angles to said cover plates to extend about the longitudinal edges of said bridge plates with adjacent extensions abutting one another and secured together and secured at their ends to the adjacent ends of said side plates, and elongated struts extended parallelly between the apexes of said bridge plates.

JOHN F. P. TATE.
